H. F. HURD,
STOCK COLLAR,
APPLICATION FILED AUG. 10, 1917.

Patented Nov. 13, 1917.

UNITED STATES PATENT OFFICE.

HUBBARD F. HURD, OF TROY, NEW YORK, ASSIGNOR TO CLUETT, PEABODY & CO., INC.,
OF TROY, NEW YORK, A CORPORATION OF NEW YORK.

STOCK-COLLAR.

1,246,271.

Specification of Letters Patent. Patented Nov. 13, 1917.

Application filed August 10, 1917. Serial No. 185,447.

To all whom it may concern:

Be it known that I, HUBBARD F. HURD, a citizen of the United States, residing at Troy, county of Rensselaer, and State of New York, have invented certain new and useful Improvements in Stock-Collars, of which the following is a specification.

Reference may be had to the accompanying drawing, and the reference characters marked thereon, which form a part of this specification. Similar characters refer to similar parts in the several figures therein.

This invention relates to a stock adapted to be worn as a collar.

The principal objects of the invention are to adapt the collar for necks of different sizes; and to provide means for threading one portion of the stock of substantially full width through an opening in another portion of the stock of substantially full width without distortion or wrinkling.

Other objects will appear in connection with the following description.

Figure 1 of the drawings is a plan view of a stock-collar embodying my invention.

Fig. 2 is a rear view in perspective showing one end of the stock threaded through the opening in the stock.

Fig. 3 is a horizontal section taken on the broken line 3—3 in Fig. 1.

Fig. 4 is a vertical section taken on the broken line 4—4 in Fig. 1.

Referring to the drawings wherein the invention is shown in preferred form, the stock has a long member, 1, and a short member, 2, each tapering toward its outer end.

The inner ends of the members, 1 and 2, are separately finished as by inturning said ends and securing the inturned edges by stitching, 3 and 4, respectively; or said ends may be finished in any manner adapted for the material of which the stock is made.

The members, 1 and 2, are secured together with their inner ends neighboring each other, by means of straps, 5, leaving an opening, 6, between the members through which the outer end of the long member, 1, can be threaded in winding the stock around the neck of the wearer.

These straps, 5, are attached to the side edges of the respective members as by inserting the ends of the straps between the

plies of the respective members made of a plurality of plies, and securing said inserted ends by edge-lines of stitching, 7.

The neighboring ends of the members, 1 and 2, are of full width, or substantially maximum width, of the body of the stock, so that the opening, 6, is adapted to freely receive the widest portion of the member, 1, threaded therethrough without wrinkling or distorting said threaded member.

This I am able to accomplish by attaching the straps, 5—5, to the side edges of the respective members, 1 and 2, whereby said straps are located outside of the general side lines of the stock-body as shown in Fig. 1.

By this construction, it is possible to secure a wide range of adjustment to adapt the stock to necks of different sizes, and at the same time to have the stock present to the neck an inner surface of full, or substantially maximum, width throughout its circumferential extent for whatever size the stock may be adjusted.

While I have shown the ends of the stock tapered, I do not wish to be limited to this feature as my invention makes it unnecessary to taper the ends, although I consider it preferable to do so.

The stock may have the usual tapes, 8, attached to the ends of the respective members, 1 and 2.

I prefer to make the stock of a plurality of plies of fabric having their edges inturned and stitched together as shown in Figs. 3 and 4, although it may be made of any desired material suitable for the purpose.

The straps, 5, may be made of narrow tape, cord or the like.

What I claim as new and desire to secure by Letters Patent is—

1. A stock-collar having a short member and a long member secured together end to end by means of straps extending along the opposite sides of the collar and attached to the side edges of the respective members.

2. A stock-collar having a short member and a long member secured together by straps end to end whereat they are of the full width of the collar, said straps extending along the opposite sides of the collar, and being attached to the side edges of the respective members.

3. A stock-collar having a short member and a long member each formed of a plurality of plies of fabric, said members being separately finished at their neighboring ends whereat they are secured together by means of straps extending along the opposite sides of the collar, the ends of each strap

being inserted and secured between the side edges of the plies of the respective members.

In testimony whereof, I have hereunto set my hand this 7th day of August, 1917.

HUBBARD F. HURD.
